UNITED STATES PATENT OFFICE.

THEODORE H. JOSEPH, OF NEW YORK, N. Y.

LOCK.

Application filed December 30, 1922, Serial No. 609,813. Renewed October 21, 1927.

This invention relates to improvements in locks, and more particularly to recording locks which are used in conjunction with ordinary locks. Recording locks, as is well-known, are provided with mechanism for making a record upon a time chart or otherwise recording the time at which said lock is operated. It frequently happens that an employee entrusted with the operation of the locks will operate the ordinary lock and leave the key of the recording lock with some unauthorized person with instructions to the latter to operate the recording lock at a given time. In this connection it should be remembered that the authorized employee will seldom take the risk of leaving both locks open, and since he does not wish to operate the recording lock before the proper time he will usually lock the ordinary lock. It is the principal object of this invention to provide means whereby such unauthorized operation of the locks is prevented.

It is a further object of this invention to provide means whereby operation of the ordinary lock is rendered impossible until the recording lock has been operated.

A further object is the provision of means for accomplishing the above objects which involves a minimum change of structure in the locks, and which is inexpensive and easily applied to present types of locks.

A further object is the provision of simple interconnecting means between the bolt of the recording lock and the ordinary lock whereby access to said ordinary lock is cut off until said bolt is operated to locking position.

Other objects and advantages will in part be obvious, and in part specifically pointed out in the specification.

To the attainments of the aforesaid objects and ends my invention consists in the novel details of construction, and in the combination, connection and arrangement of parts hereinafter more fully described and then pointed out in the claims.

In the accompanying drawings,

Figure 1 is a front elevation of a portion of a door and jamb having a recording lock and a primary lock and showing my invention attached thereto, parts being broken away to disclose the underlying structure;

Fig. 2 is a view similar to Fig. 1 but with the locks in different operated positions;

Fig. 3 is a side view with parts broken away of the device shown in Fig. 1;

Fig. 4 is a perspective view of the operative connection between the locks;

Fig. 5 is a view similar to Fig. 1 showing a modified structure of operative connection between the locks;

Fig. 6 is a view similar to Fig. 5 with the locks in different operative positions;

Fig. 7 is a side elevation, partly broken away of the device shown in Fig. 5, and

Fig. 8 is a perspective view of the bolt employed in the recording lock of Fig. 5.

Referring to the drawings, there is shown an ordinary lock 10, hereinafter termed the primary lock, and a recording or secondary lock 11, both locks being of the barrel type and having their cylinders affixed in the usual manner to a door 12. The recording lock is provided with recording mechanism 15 which may be of any usual type, and with a bolt 14 operating in a keeper 16 fixed to the door jamb adjacent the door opening. The primary lock is preferably positioned beneath the recording lock although the invention applies where a different arrangement is employed.

A sleeve 20 extends substantially through the door and has a flange 21 at its front end resting against the outer face of the door and a flange 22 preferably screw-threaded on its other end within a cavity 23 in the rear face of the door. It will be understood that the sleeve is forced inwardly from the outer face of the door and the flange 22 is then screw-threaded upon its inner end to hold the sleeve fixed in position. A connecting member 25 in the form of a bell crank arrangement has a shaft 26 extending through said sleeve and has formed, preferably integral therewith, an arm 27 on its outer end to operate over the outer surface of the door, and an arm 28 on its inner end operating in cavity 23 within the door. The arm 28 is provided at its free end with a pin 29 which extends rearwardly from arm 28 into a cam slot formed in the bolt of the recording lock. The said pin 29 may be provided with an anti-friction roller 30.

The angle at which arms 27 and 28 are disposed relative to each other, and the inclination of slot 35, may be varied at will to accomplish the desired function, i. e., to rotate arm 27, when the bolt 14 is operated to locking position, from a position directly over key-hole 36 of lock 10, (as in Fig. 1) to a position such that said key-hole is exposed (as in Fig. 2); and to restore the arm

27 to the position where it covers key-hole 36 when the recording lock is opened. As shown, the arms 27 and 28 are substantially at right angles, the arm 27 extending downwardly to cover key-hole 36. The cam slot 35 is shown inclined downwardly to the right, so that as the bolt is shot, the arm 28 rides upwardly to rotate member 25, and hence the arm 27. An enclosing casing 39 for arm 27 may be fixed to the door by screws extending from the rear of the door into threaded openings 38 in lugs fixed to said casing, the latter having an opening 40 opposite the key-hole of lock 10.

15 It will thus be apparent that an employee cannot lock primary lock 10, and entrust locking of the recording lock to some unauthorized person, because the primary lock cannot be operated until the secondary lock 20 has first been operated.

In Figs. 5 to 8 is shown a modified structure for accomplishing the same functions as the device shown in Figs. 1 to 4. The same primary and secondary locks 10 and 11 may be employed and enclosed by a casing 39' secured to the door, and provided at its lower portion with a circular opening 40' registering with the key-hole 36 of said primary lock 10. Beneath the cylinder of the recording lock a sleeve 45 extends completely through the door and has flanges 46, 47 at its ends. A shaft 48 extends therethrough provided with pinions 49 and 50 at its ends. The flange 47 and the pinion 50 extend beyond the door into the space occupied by the bolt 14'. The latter is provided with a cut-out portion 53 to accommodate said flange and pinion while permitting operation of the bolt. The connecting member between the locks is in the form of a U-shaped frame or member 55 working in guides 55^a provided on the casing 39', and having a rack 56 formed upon one of its vertical members and meshing with pinion 49. The lower end of said frame or member, in the raised position thereof, covers the key-hole 36 of the primary lock. The said cut-out portion 53 has the upper horizontal limiting wall thereof provided with a rack 60 which meshes with pinion 50. It is apparent that when bolt 14' is shot, the pinions 50 and 49 will be rotated to lower the frame 55 and uncover the key-hole 36, and that when bolt 14' is retracted the key-hole 36 will be again covered up.

55 The above description illustrates the principles embodied in my invention, but it will be understood that various changes and modifications may be resorted to within the scope of my invention as defined in the annexed claims.

Having thus described my said invention, what I claim and desire to secure by Letters Patent is:

65 1. An apparatus of the character de-

scribed, comprising a primary lock and a secondary lock operatively associated with respect to the same door, independent actuating means for each lock, and means operated by the actuation of said secondary lock, serving to render the actuating means of said primary lock inaccessible while said secondary lock is unlocked.

2. An apparatus of the character described, comprising a primary lock and a secondary lock operatively associated with respect to the same door, separate actuating means for each lock, and means operated by the actuation of a movable part of said secondary lock, serving to render the actuating means of said primary lock inaccessible while said secondary lock is unlocked.

3. An apparatus of the character described, comprising a primary lock and a secondary lock operatively associated with respect to the same door, and including separately operable bolts, and a member operatively associated with the bolt of said secondary lock, serving to prevent the introduction of the key of said primary lock 90 thereinto while the bolt of said secondary lock is adjusted to unlocking position.

4. An apparatus of the character described, comprising a primary lock and a secondary lock operatively associated with respect to the same door, and including separately operable bolts, and a movable member operatively associated with the bolt of said secondary lock; said movable member having a part serving to mask the key hole 100 of said primary lock and to prevent the introduction of a key into said primary lock while the bolt of said secondary lock is retracted.

5. An apparatus of the character described, comprising a primary lock and a secondary lock operatively associated with respect to the same door, and including separately operable bolts, a movable member operatively associated with the bolt of said secondary lock, and a casing for said primary lock having an opening therein registering with the key hole of said primary lock; said movable member having a part extending into said casing and serving to 115 mask the key hole of said primary lock when said secondary lock is unlocked.

6. An apparatus of the character described, comprising a primary lock and a secondary lock adapted to be operatively associated with respect to the same door, a member serving normally to permit the insertion of the means for actuating said primary lock, and a connection between said member and said secondary lock whereby 125 said member is rendered inoperable when said secondary lock is locked.

7. An apparatus of the character described, comprising a primary lock and a secondary lock adapted to be operatively as- 130

- sociated with respect to the same door, and a bell-crank between said locks, said crank having one arm adapted to prevent access to said primary lock when said secondary lock is unlocked, and having a second arm connected to said secondary lock whereby said crank is rotated when said secondary lock is locked to move said first arm to ineffective position.
- 10 8. An apparatus of the character described, comprising a primary lock and a secondary lock having a bolt, both locks being operatively associated with respect to the same door, and a bell-crank between said locks, said crank having one arm directly over said primary lock when said secondary lock is unlocked, and said bolt having a cam slot in which another arm of said bell-crank engages so that when said bolt is shot said 15 crank is rotated to move said first arm to ineffective position.
9. An apparatus of the character described, comprising a primary lock, a secondary lock having a bolt, separately operable, both locks being operatively associated with respect to the same door, means controlled by the bolt of said secondary lock for preventing the introduction of means for operating said primary lock when said 20 secondary lock is unlocked, and means whereby the means controlled by said bolt is adjusted to ineffective position when said bolt is shot.
10. An apparatus of the character described, comprising a primary lock, a secondary lock having a bolt, both locks being 25
- operatively associated with respect to the same door, means for preventing operation of said primary lock when said secondary lock is unlocked, and means operatively connected at one end to said bolt and at the other end to said first-named means whereby said first-named means is moved to ineffective position when said bolt is shot.
11. An apparatus of the character described, comprising a primary lock, a secondary lock having a bolt, both locks being operatively associated with respect to the same door, means for preventing operation of said primary lock when said secondary lock is unlocked, a rotary shaft, a connection between said shaft and said means, and a connection between said shaft and said bolt whereby to render said means ineffective when said bolt is shot.
12. An apparatus of the character described, comprising a primary lock, a secondary lock having a bolt, both locks being operatively associated with respect to the same door, means controlled by the bolt of said secondary lock for preventing the introduction of actuating means for operating said primary lock when said secondary lock is unlocked, and means whereby said first-named means is operated to ineffective position when said bolt is shot and to effective position when said bolt is retracted.

Signed at the city of New York, in the county and State of New York, this 2nd day of November, one thousand nine hundred and twenty-two.

THEODORE H. JOSEPH.
